UNITED STATES PATENT OFFICE

JOHN F. MARTIN, OF SPRINGFIELD, MASSACHUSETTS, ASSIGNOR TO UNITED AMERICAN BOSCH CORPORATION, OF SPRINGFIELD, MASSACHUSETTS, A CORPORATION OF NEW YORK

DUST PROTECTOR DEVICE

Application filed February 26, 1931. Serial No. 518,482.

This invention comprises improvements in protective devices, and especially means for safeguarding mechanism against the entrance of dust and thus prevent the injurious effects which dust will always produce.

It is an object of the invention to provide simple and effective means for sealing the casing or housing of virtually any type of enclosed apparatus having moving parts operated by a projecting drive shaft, at the place where said shaft enters the casing or housing, and to arrange the sealing means so that the desired result will not be lessened by wear due to long continued use.

A further object is to provide sealing means including a member carried by the projecting drive shaft of an enclosed mechanical apparatus, at the place where the shaft enters the casing or housing of the latter, and a portion of said casing or housing that is designed to cooperate with said member to bring about the full dust-excluding action.

Another object of the invention is to provide a dust protector which can be utilized with enclosed apparatus as above set forth, and which will serve the purpose of not only obstructing the admission of dust to the interior of the casing or housing, but also of trapping the dust in suitable recesses, which can readily be emptied, so that the dust protector can easily be kept clean.

The nature of the invention and the peculiar merit and advantages thereof are explained in the following description and accompanying drawing, which show a number of embodiments of my protective devices. The disclosure, however, is illustrative only, and I may make alterations in the various parts within the scope and meaning of the broad terms in which the novel features of the invention are defined.

On said drawing,

Fig. 1 is a side view, partly in section, of one form of my invention; and Fig. 2 is a vertical transverse section on the line 2—2 of Fig. 1.

The same numerals identify the same parts throughout.

In the particular description of what the

drawing presents, I employ the numeral 1 to indicate the body of an electrical magneto such as is commonly used to furnish ignition current for internal combustion engines. The magneto has an end plate 2, and is driven by a shaft 3, which is connected with the armature of the magneto through a so-called impulse coupling 4. This coupling, as is well known, is constructed so that it has no effect at the regular speed, but in starting it causes the armature to be momentarily retarded and then thrown forward with an accelerated motion to generate enough energy for the spark. This impulse coupling has a casing or housing, part of which is depicted at 5, affixed to or made integral with the end plate 2. Magnets with such couplings are generally much exposed to dust and dirt, and it is quite important and desirable to protect the couplings, as well as the inside of the magneto, which usually has its armature chamber in line therewith. The part 5 of the casing has a reduced terminal rim with an exterior shoulder 6, and the remainder of the casing is in the form of two semi-cylindrical halves 7, with a reduced rim and interior annular shoulder 8. The rim with the shoulder 8 fits upon the rim of the part 5, and two shoulders 6 and 8 may abut to make a good fit. Transverse bolts 9 engaging holes in the halves 7 hold the latter tightly together, and cause them to grip the reduced rim of the part 5 securely, to make the housing of the coupling complete. The halves or sections 7 can thus be quickly assembled with the part 5 around the shaft 3, and can be dismounted whenever necessary merely by taking out the bolts 9.

The part of the casing made up of the sections 7 has a reduced extension 10 within which is a spiral spring element 11 held fast to the casing by a rivet 12. Surrounding the shaft within this extension is a member or packing sleeve 13 of felt or some other material, and the free end of the spring 11 surrounds and presses upon this packing. The front of the extension is closed by a wall 14, having an opening 15 through which the shaft 3 passes. The spring 11 is of the clock

- type; it is light in weight, and in rest position it exerts very little pressure on the packing. It is disposed in the casing in such position that, when the shaft 3 rotates in the 5 direction of the arrow in Fig. 2, the tendency is to wind up and tighten this spring. Of course, the sleeve 13 is loose upon the shaft 3, but the shaft will exert a turning force thereon due to friction, and it may rotate 10 therewith to a slight extent. But as soon as the turning of the sleeve winds up the spring tight enough, the spring holds the sleeve stationary. Hence a perfect sealing is obtained, and is not diminished by the 15 wear of the packing. The edge of the packing is also held by the spring firmly against the inner face of the wall 14; and thus the housing for the coupling 4 is closed perfectly.
- 20 To affix the sections 7 more surely upon the part 5 of the housing of the coupling, I may further attach to this part and to the sections alined lugs 16, with openings for bolts 17. These bolts will hold the sections 25 7 to the part 5 more securely than the bolts 9. Obviously, my invention can be practiced with any enclosed mechanism, and a magneto with its encased impulse coupling is mentioned above only by way of example.
- 30 Having described my invention, what I claim is:
1. A protective device for apparatus arranged in an enclosing casing, with a rotary shaft entering the casing to drive said apparatus, said device including a member on the shaft and an element affixed within the casing adjacent one end and encircling said member adjacent the opposite end to be put under stress when the shaft revolves to 35 cause the member to engage the shaft tightly and seal said casing.
  2. A protective device for mechanism enclosed in a casing and having a rotary shaft entering the casing to operate said mechanism, said device comprising a packing sleeve on the shaft within the casing at the place where the shaft enters the latter, and a spring attached at one end to the inside of the casing, and encircling the packing at its 40 opposite end to cause the packing to seal the casing.
  3. A protective device for mechanism contained in an enclosing casing and having a shaft projecting into the casing to operate said mechanism, said device comprising a packing sleeve on the shaft inside the casing at the point where the shaft enters the latter, a coiled spring affixed to the inside of the casing at one end and encircling the 45 sleeve at the other end, and arranged so that the rotation of the shaft in one direction tends to make the sleeve wind up the spring and the spring to press the sleeve against the shaft to seal the casing.
  4. A protective device for mechanism con-

tained in an enclosing casing and having a rotary shaft projecting into the latter to operate said mechanism, said device comprising a packing sleeve on the shaft inside the casing where the shaft enters the latter, a coil spring engaging the inside of the casing at one end and encircling the sleeve at the other end and arranged so that the rotation of the shaft tends to make the sleeve wind up the spring and the spring depress the sleeve against the shaft to seal the casing.

5. A protective device for apparatus arranged in an enclosing casing, with a rotary shaft entering the casing to drive said apparatus, said device including a packing member on the shaft in the casing adjacent where the shaft enters the latter, and a yielding element engaging the casing at one end and encircling said member adjacent the other end to cause said member to engage said shaft tightly and seal the casing when the shaft revolves.

In testimony whereof I affix my signature.

JOHN F. MARTIN.
